(57) CLAIM

The ornamental design for a jewellery bag, as shown and described.

DESCRIPTION

FIG. 1 is a perspective view of a jewellery bag showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a front view of an opening state of the jewellery bag thereof.

The broken lines shown in the drawings depict portions of the jewellery bag in which the design is embodied that form no part of the claimed design.
